UNITED STATES PATENT OFFICE.

CHARLES C. KRIEBLE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING MACHINE.

Original application filed September 19, 1922, Serial No. 589,094. Divided and this application filed May 2, 1924. Serial No. 710,627.

The invention is designed particularly for making neckties, but is not limited to such use.

The invention consists in the features and combination and arrangement of parts hereinafter described, and particularly pointed out in the claims.

The claims appended hereto are directed to subject matter divisible from that 10 claimed in application Serial No. 589,094, filed September 19, 1922, now Patent 1,525,- 610, Feb. 10, 1925.

In the accompanying drawings:—

Figure 1 is a front view of a knitting machine embodying the invention.

Fig. 2 is a side elevation.

Fig. 2^a shows details.

Fig. 3 is a plan view.

Fig. 4 is a detail plan view.

Fig. 4^a is a detail.

Fig. 5 is a developed view of the sets of needle cams and trick wheels, showing also diagrammatically the needle wave and the 25 yarn feed ends.

Fig. 6 shows the device for lowering the stitch cam.

Fig. 7 shows the star wheel and ratchet used for various purposes.

Fig. 8 is a view of the stitch cam post.

Fig. 9 is a view of the needle raising cam post.

Fig. 10 is a plan of the cam box and associated parts.

Fig. 10^a is a side view of a part of the 35 cam box at the position of the stitch cam post.

Fig. 10^b is a similar view at the position of the needle raising cam post.

Fig. 11 is a sectional view of the cam box. 40 Figs. 12, 12^a, 13 and 14 are views of power transmitting slides.

Fig. 15 is a view of a portion of the jac- 45 quard paper strip.

Fig. 16 is a detail view.

Figs. 17, 18, 19 and 20 are views of details relating to the selector devices.

Fig. 21 is a plan view of the gear for driving the needle cylinder and certain cams mounted thereon.

Fig. 22 is a sectional view of the needle cylinder and the gear for driving the same.

Figs. 23 and 24 are views on a reduced scale of a bracket for supporting and guiding certain parts.

Figs. 25 and 26 are views of guide means 55 for the yarn feed fingers and the yarns.

Figs. 27 and 28 are views of pull and push pawls.

Figs. 29 and 30 are views of a ratchet cam ring. 60

Fig. 31 is a view of a detail.

Fig. 32 is a detail plan view of parts shown in Fig. 3.

Fig. 33 is a side view of one of the pull bars, its slide and the ratchet driven thereby. 65

Fig. 34 is a side view of another one of the pull bars and the means operated thereby.

The machine has a revolving needle carrier 1, the needles being indicated at 2.

There is a group of main yarn guide fingers at each side of the machine, these being for different colors of kinds of yarn. The fingers 3 of each group are pivotally mounted side by side at 4 in brackets 5 fixed to the sinker cam ring 6 which is held against rotation by a stud 7 extending from a bracket 8, said stud entering a notch in the cam ring.

The main yarn fingers 3 incline downwardly and inwardly from their pivots towards the axis of the machine and feed the 80 yarn to the needles through mouths 10, 10' of a latch guard ring 11 fixed by screws 12 to the stationary top plate or sinker cam ring of the machine. These fingers are thrown down into operative position by vertical push rods 13 mounted to slide in the brackets 5. These push rods are operated

selectively by a plunger 14 which is positioned under the proper push rod by the movement of a carrier block 15 which is 85 slidably mounted in the bracket 5. The lower end of the plunger rests upon a lifter plate 16 which is of sufficient width to insure contact with the lower end of the plunger in all positions to which the latter may be moved

by the carrier according to the demands of the pattern mechanism, as will be described hereinafter. This lifter plate is pivoted at 17 to the fixed bracket and it has a roller 18 designed to be acted on by a rotary cam member 19, fixed beneath the rotary sinker bed. This cam operates the lifter, at each 90 revolution of the machine, and if the plunger 14 has been moved by its carrier 15 to a position under one of the push rods 13 (there

being four in each group) the rise of the outer end of the lifter will elevate the plunger 14 and cause it to push up on the proper 105

rod 13, which, acting on the tail 3' of the yarn finger, will throw this down to feeding position. The cam 19 has an incline 19' which gives to the roller 18 its downward movement sufficient to lower the yarn finger, as just stated, to feeding position. It has an additional rise 19'' which gives the yarn finger a slight additional downward movement, the result of which is that a projection 3'' of the depressed finger will throw down a latch plate 20, and as soon as the finger has reached its final position the latch plate will rise under the action of its spring 20' and said operated yarn finger will be retained in its operated position to continue feeding the yarn. The same action, just described, which results in the depression of the latch plate by the movement of the operated yarn finger downward to feeding position, will release any one of the yarn fingers of this group, so that this will rise and withdraw its yarn from work. This rise of the released yarn finger will be due to the action of the spring 3^a with which each yarn finger is provided at its pivot. Fig. 1 shows one finger in low or feeding position held by the latch plate and the upper or released position of one of the fingers is also shown. The release of a finger from feeding position, above mentioned, is due to the fact that when the new yarn finger is thrown down, its projection engages and presses down the outer end of the latch plate by working against the upper surface of its upstanding latch portion and carries this low enough to release the projection 3'' of the finger which has been feeding. Any push rod 13 which may be operated, can fall down to normal position as soon as the plunger 14 moves away from its lower end, and in this lowered position the push rods rest upon the upper surface of the plunger's carrier block 15. The plunger itself is under tension of a spring 14' (seated between the walls of the carrier, which is channel shaped) which forces it downward when the lifter plate 16 falls. In its upper position the plunger will be retained by a detent 14'' which is in the form of a leaf spring 14^a having the detent projection 14'' to enter a notch 14^a in the plunger, i. e., the same notch which the end of spring 14' lies in, but this happens only when the carrier 15 is at the left hand limit of its stroke, which is its normal position. The holding up of this plunger also has the effect of keeping the lifter plate 16 up, so that its roller, which is then down, will not be hit by the rotary cam 19, and therefore the lifter plate will not flap up and down idly. This condition is illustrated in the right of Fig. 1. When, however, the plunger carrier 15 is moved to the right, Fig. 2, from its normal position of rest at the left of the group of push rods, the plunger will move away from and will no longer be re-

tained by the detent, and hence the spring of the plunger will force it down and thus tip the lifter plate into position, so that its roller will be within the range of the cam 19 and hence will be operated by said cam to swing the outer end of the plate upwardly and thus raise the plunger to move the proper yarn finger into feeding position and release the other finger, so that it may rise to inoperative position under the action of its spring. This downward movement of the plunger when the carrier moves to the right is due also to its working against an incline 14^b on the frame or bracket.

The plunger carrier is moved towards the right from its left-hand position shown in Fig. 2, by pattern mechanism as follows:

A rod 21 connects the sliding carrier with a lever 22, fixed to a shaft 23 mounted in the fixed bracket 8 supported on the fixed base 24 of the machine. This shaft 23 is operated by an arm 23' whose hub is pinned thereto at 23'', the depending end of which arm engages a notch 25' in a slide 25, Figs. 3 and 12, which has pivoted at 26 four pull bars 27, Fig. 3, each of which rests upon one of the pins 28 mounted in a carrier bar 29, so as to slide freely therein, in a substantially vertical direction. This carrier bar has movement up and down to the perforated pattern strip or jacquard device which in the present case consists of an endless sheet of flexible material, as paper 30', passing over a pattern drum 30 referred to more fully hereinafter. The up and down movement of the pin carrying bar is derived from a cam 31 arranged coaxially with the needle cylinder and adapted to operate against a roller 32 carried by a slide 33 which is guided in the bracket 34, Figs. 2 and 4. This slide bears against an eccentric pin 35' carried by a rocking arm 35 which is pivotally mounted at 36 and is connected with an arm 37 which has thereon the pin carrying bar 29. A spring 38 presses the arm down and the cam 31 through the connections described, raises the pin carrying bar. When the pin carrying bar is raised it engages the heads of the pins and holds them up. The jacquard strip is perforated and is moved step by step by the intermittent movement of the drum 30 which has teeth 30^a engaging marginal openings in the strip. Now when the pin carrying bar moves down, any pin which finds an opening in the paper strip will pass therethrough, but any pin which strikes an imperforate part of the strip will be held up, despite the fact, as just stated, that the pin carrying bar has lowered. The pin which passes through the perforation in the paper strip will, of course, move down and this will allow the pull bar 27, Figs. 2^a and 3, which is resting thereon, to fall also, and this will bring a shoulder 27' on the pull bar into

range of an oscillating push plate or bar 39 with the result that, supposing the push plate is moving towards the left in Fig. 2, the pull bar 27 which has fallen will be pushed leftward and drawing upon the slide 25 will operate the arm 23' which engages its notch 25', Fig. 3, and turn the shaft 23, thus swinging the arm 22 towards the right and moving the plunger carrier 15 rightward to bring the plunger 14 under the proper push bar 13 for operating the corresponding yarn feed finger into operative position, when the lifter plate 16 moves upwardly. The train of connections just described will be returned to normal position, as will be hereinafter described. The pull bar which has been operated, as just described, will be elevated to normal position by the rise of the pin carrying bar 29 which will elevate the pin upon which said pull bar rests, and when raised to this normal position, the said pull bar will be out of range of movement of the oscillating bar 39, ready for another action such as just described, when the pattern strip calls for it. As before stated, there are four pull bars 27 connected with the one slide 25, and the shoulders 27' of these pull bars are in line with each other, see Fig. 3, but it will be noticed that the oscillating bar 39 has a series of shoulders 39' in stepped relation, and consequently at different distances from the shoulders 27' of the pull bars 27, so that the slide 25 will be moved different distances, according to which one of the four pull bars is lowered into range of the oscillating bar 39. The bar 39 oscillates always through the same length of arc, it being mounted on a frame 39'' pivoted at 39^x to the bracket 34, Fig. 2, and it is operated as will be described hereinafter. If the first one of the pull bars 27 (counting from the bottom of Fig. 3) is the one lowered, then the oscillating bar 39 will move this the maximum distance, because its shoulder 27' stands nearest to the edge of the bar 39. This pull bar will therefore cause a full rightward movement of the plunger carrier 15 and the plunger 14 will select the right-hand push bar 13 to throw the right-hand yarn finger down to operative position. If the second pull bar 27 is lowered, there will be some lost motion of the oscillating bar 34, so that the plunger carrier 15 will not be moved so far to the right as in the first instance, and consequently the plunger 14 will select and operate the second yarn finger (counting from the right of the group A, Fig. 3) and so on, as to the other pull bars 27, each in order being operated to a lesser degree than the preceding one, owing to the stepped formation 39' in relation to the shoulders 27' of the pull bars.

65 The train of mechanism just described has relation to the group of yarn fingers A. A similar operation takes place in relation to the group of yarn fingers indicated at B, Fig. 3. There is a plunger carrier 15^a for this side of the machine with rod 70 21^a, lever 22^a, and a shaft 23^a, which latter is arranged axially in line with the shaft section 23 above mentioned, and this shaft section 23^a is operated through an arm 23^b fixed thereon from a slide 25^a which is like 75 the slide 25 and has four pull bars 27^a pivoted thereto, to be controlled by certain of the pins 28 and operated severally by the same oscillating bar 39 when the pins find openings in the jacquard strip through 80 which to pass when the carrier bar 29 is lowered.

It will be noted that the fingers of group A may be selected in any prescribed order desired, the variations in the order of selection depending upon the disposition of the holes in the jacquard strip, and this is true also of the group of fingers B and the order of selection of one group may be entirely different from that of the other group. 85 In other words, the two groups are entirely independent of each other in the sense that the order of selection of the fingers of one group may vary indefinitely in respect to the other group, though the selection in 90 respect to the two groups is derived from the same source, i. e., the jacquard strip.

The push plate 39 is operated by a spring 40 in one direction, this spring being connected to the swinging frame 39'', and in the other direction the operation is due to a cam 41 operating against a roll 42 mounted on a slide 33' which bears against an adjusting screw 43 carried by the frame. The eccentric pin 35' of the lever 35 may be turned 100 for adjustment of its contacting relation with the slide 33 by a screw driver, the head of this pin being kerfed, and when adjusted it is held by a set screw 35''. The rocking of the frame 39'' is utilized for operating 105 the pattern drum step by step, for which purpose the frame carries a pawl 44 to engage the teeth 45 of the drum. This pattern drum is substantially like that shown 110 in an application of Howie and Taylor, Serial No. 549,253, filed April 3rd, 1922. It involves a rotary part 30 which has the teeth which drive the pattern strip and a stationary part 30^a which is fixed to the 115 bracket arm 30^b at 30^c and this stationary part has the opening or openings 30^d through which the pins 28 pass when an opening in the jacquard strip aligns therewith and when the pin is lowered by the bar 29.

120 In order to return the carrier slide 15 to normal position at the left of Fig. 2, after being operated to the right (it being observed that the pull bars 27 have only the advancing shoulder 27', but not the return shoulder, see Fig. 3) the lever 22 has a 125 130

downward extension 22^x connected by a rod 46 with an arm 47 on a vertical shaft 48 mounted in the fixed base of the machine and in a bearing 49, Fig. 1, and this shaft 5 carries an arm 50 fixed thereto which is in the path of a roller 51 on the shaft 52 forming a part of the rotary take-up mechanism. This mechanism may be of any suitable type and needs no detailed description herein, except to say that the revolving frame of this takeup mechanism is shown at 53, and this affords bearings for the shaft 52, one of which is indicated at 54. The shaft is driven by a gear 55 meshing with a circular rack 56 which is supported in fixed relation to the frame by arms 57. The shaft 52 carries the clutch 58 which drives the take-up rolls located within the fabric cam 59 and not shown, these rolls being journaled in the revolving take-up frame 53. The roll 51 travelling about the axis of the machine will hit the arm 50 and through the rock shaft 48 and the connections just described, the lever 22 will be returned to the normal position shown in Fig. 2, with the selector plunger 14 at the left of the series of push rods 13 and with the pull bars 27 restored to normal position.

30. *Needle cams.*

The machine, being a two feed type, there are two sets of needle cams, shown in Fig. 5, consisting of stitch cams *a*, *a'*, raising cams *b*, *b'*, and fixed cam pieces *c*, *c'* and *d*, *d'*, and there are two trick wheels *e*, *e'*, at diametrically opposite sides of the machine.

Each of the stitch cams is adjustable automatically to knit tight or slack and for this purpose each is screwed to a post 59 which is normally pressed upwardly by a spring 59' pressing against a lateral projection 59" of the post, the spring being seated in a pocket of the cam block, as in ordinary practice. For automatically lowering the stitch cam against the pressure of this spring, the post is notched at 59^x and a crank member or pin 60 enters this notch. This crank pin is journaled in the cam block and on its outer end it has fixed thereto an arm 60' carrying a screw pin 60" to bear on a controller ring 61, Fig. 1, which on its edge is formed with ratchet teeth 61' and on its upper surface is formed with high and low surfaces 61^a and 61^b. The controller ring is moved step by step by a pawl 62 pivoted to a lever 63, Fig. 3, which is pivoted at 64 to the base of the machine and is operated by a slide 65, guided in the frame of the machine and having connected pivotally thereto at 66 a pull bar 67 which, like the pull bars before described, is operated leftward, Fig. 3, by the push plate 39. This pull bar has two shoulders, like the one which appears in Fig. 2, so that the push plate 39 will engage one shoulder to advance the pull

bar leftward to turn the controller ring in the arrow *y* direction, Fig. 3, and when the push plate 39 returns to the right it will engage the other shoulder of the pull bar and return it to normal position to retract the pawl for a fresh operation. No detent is required to hold the controller ring against overthrow, as the action is not rapid and the friction is sufficient to prevent undue movement. One step movement will cause 75 a high part of this controller ring 61 to tip the arm 60' up and this, as indicated at the right of Fig. 5, will cause the flat face of the pin 60 to engage the lower shoulder of the cam post 59 and lower the stitch cam 80 for making slack stitches, and when the next step movement of the controller ring takes place, according to the demands of the pattern mechanism, the low part 61^b of the controller ring will allow the arm 60' to lower, thus turning the crank pin, so that the spring 59' then becomes effective to raise the cam post 59 and allow the stitch cam to assume position for knitting normally tight.

The control just described is exerted at both feeds simultaneously, because the turning of the controller ring will operate the stitch cams *a* and *a'* simultaneously, it being understood that there is a crank pin 60 and arm 60' at each of the stitch cams. The knitting of the slack course is for making, for instance, the neck band portion of the necktie.

The needle raising cams *b*, *b'* are pressed normally downward by springs 68 and they are raised by star wheels or cams 69 which lie in the notches 69' of their posts 69", the springs being pocketed in the posts and held in place by overlying plates 69^x fixed to the cam box. The star cams are formed in one piece with the hubs 70 of ratchet wheels 70' which are turned step by step, and at such intervals as are prescribed by the pattern mechanism, by pawls 70".

The hubs 70 are journaled in the cam housing or box 71. The pawls 70" are reciprocated once for each revolution of the machine. They are pivotally connected with rocking arms 70^x mounted on a shaft 70^a, Fig. 2. The arm 70^x is rocked by a rod 72, Figs. 2 and 3, connected with a bell crank 72' pivoted to the base of the machine and operated by a slide 72" having a pin 70^x engaging a notch in the bell crank lever. The slide moves in a guide-way in the base of the machine and at its inner end it has a roller 73, dotted lines Figs. 1 and 3, adapted to be struck by cams 73', 73", the former of which moves the slide radially inward, and the latter of which moves the slide radially outward. These cams are carried by the bevel gear 74, dotted lines, Fig. 1, which transmits rotary motion to the needle cylinder, it being driven by the bevel 130

gear 74' on the main drive shaft 74", Fig. 1.

Not every stroke of the pawls 70" is effective in turning the ratchet wheels 70', but only when the pattern mechanism calls for it. For controlling these pawls star cams 75 are provided, one of which is shown in Fig. 2, and both of which are shown in Fig. 3. These star cams are connected or formed with ratchet wheels 75', these being mounted

- 10 to turn freely about the shaft sections 23, 23'. The pawls 70" simply rest on the star wheels and when these are turned to present their high points beneath the pawls the latter will be lifted so as to miss their 15 ratchets 70' and hence no change in the position of the needle raising cams *b*, *b'* will take place, whereas when the ratchet wheels 75' are given their next step movement, the flat or low sides of the star cams will come under 20 the pawl bars 70" and these will lower so as to engage and turn the ratchet wheels 70' on their next stroke to the right, thus to adjust the needle raising cams *b*, *b'* vertically.

- 25 The ratchet wheels 75' are turned step by step by pawls 75" pivotally mounted at 75" to slides 76, one for each side of the machine, Fig. 3, each of which has a pull bar 76' resting on one of the pins 28 to be controlled thereby as to its up or down position in respect to the push plate 39 which is to operate them in a manner before described. Each of these pull bars is advanced and retracted by the push plate 39.

- 35 The vertical adjustment of the needle raising cams cooperates with trick wheels in forming the pattern. If these cams are in their lower positions those needles which are not raised to clear their latches will pass 40 these cams in tucking position and tuck stitches will be formed on these needles, while those needles whose butts engage the seats in the trick wheel will knit, whereas if these raising cams are in their elevated 45 positions all needles will knit, because those which pass by the trick wheels in tucking position will be raised by the cams *b*, *b'* to clear their latches and hence these needles also will knit.

50 *Auxiliary yarn fingers.*

Supplemental yarn feed fingers are shown at *f* and *g*. These are pivotally mounted in a bracket 77 and are raised and lowered by 55 push rods 77' and springs, as at 77". The push rods are operated by star cams at 78, Fig. 2, turned by ratchet wheels 78'. Pawls 78" turn the ratchet wheels and these pawls are worked by levers 79 loosely mounted 60 on the shaft 23 and operated by slides 79', 79", which are operated by the pull bars 80, 80', of the pattern mechanism. These fingers are adapted to feed only those needles which are raised to knitting position by 65 the trick wheels. They will not feed those

needles which leave the trick wheel in tucking position and hence variations in the pattern can be produced by throwing these auxiliary fingers into and out of work. These auxiliary fingers, when lowered to feeding position, lie just below the elevated throat 10" of the ring 11, see diagram Fig. 5, so that they feed the yarn over the edge of this throat to the needles which are fully elevated by the trick wheel. This feeding 75 position of the auxiliary yarn finger is indicated at *f*, Fig. 5, and its raised position at *f'*. The raised position of the other auxiliary yarn finger is indicated at *g*. Its feeding position is at the same low level of 80 the finger at *f*. This difference in the elevated positions of these two fingers is for the purpose of preventing the two yarns from winding or twisting together clear up to the yarn fingers from the center of the 85 fabric, which, if it happened, would prevent the yarns from being fed to the needles properly when the auxiliary is lowered to feeding position. In other words, by giving a separated position to the two auxiliary yarn fingers when raised equal to the 90 distance between *f'* and *g*, the two auxiliary yarns are kept apart, so that each may be lowered to feeding position individually without interference by the other yarn. 95 The feeding position of the main yarn fingers is indicated at *A'* and their elevated positions at *A*. They lie, when lowered to feeding position, in the throat space 10. The height of the needle wave resulting from the trick wheel seats *e'* lifting certain of the needles, is indicated at *e''*, and the low wave line at this point due to the needle butts passing through the cuts *e'''* in the trick 100 wheel periphery, is indicated at *e''''*. The wave line passing the main yarn fingers may be low, as indicated at *b''*, if cam *b'* is down, or it may be higher up, if cam *b'* is raised, but in either case, the yarn will be taken by all of the needles at this point. 105 The feed mouth for the other group of yarn fingers *B* is shown at 10'. A guide finger *o* projects up from the throat 10" to properly control the yarn fed over the edge of 110 the throat.

The main yarn fingers when lowered to feeding position, direct the yarn between or alongside of guards *p*, three in number, and consisting of thin plates depending from a bar *p'* extending across and secured to the top of the ring 11. These plates have their lower edges inclining downwardly and inwardly towards the center of the machine and direct the idle yarns from the fingers, which are raised, towards the machine's axis, where these idle yarns are twisted into a rope or cord form. This action is also assisted by a guard *p''* consisting of a wire attached to bar *p'* and inclining downwardly and inwardly. When a yarn finger 115 120 125 130

is raised, the point where this yarn is tied into the fabric, of course travels with the needle row and this idle yarn, by coming against the inclined edges of the guards p and p^2 , which in effect present a depending cone formation with apex downward, will be directed downwardly and to the axial center of the machine, where they will be twisted together, but by the use of the guards the yarns will be kept separate for a considerable length thereof extending from the yarn fingers, and thus each may be lowered individually without interference by the other yarns, it being observed that the point where the twisting begins is below the level of the feeding positions of the yarn fingers. Suppose in Fig. 3 that one of the yarn feed fingers is lifted out of work, The end which is tied into the fabric will travel in the arrow direction and extend across the interior of the needle cylinder, but it will be depressed at its center by sliding down the inclines of the plates p and bar p^2 , and as the rotary movement continues and additional idle yarn is drawn off, it will twist together at the center of the cylinder.

I provide means for counting the number of neckties knit. This consists of counting mechanism C, Fig. 2, operated by a rod 81, Fig. 2, from a lever 82, the lower arm of which is operated by a slide 83, Fig. 3, having a pull bar 84 controlled by the pattern mechanism before described.

35 Reverting to the yarn finger selecting mechanism and particularly to the action of the plunger 14 and the return arm 50, it will be observed that this return arm, when struck by the roller 51, will return the plunger carrier 15 towards the left, Fig. 2, until the plunger 14 gets under the cam incline 14^b of the bracket. Further movement of the plunger carrier leftward will be due to the rise of the plunger under the action 40 of the lifter plate 16, which will force the plunger up into contact with the said cam incline 14^b and thus shift it further leftward. This will have the effect of throwing the return arm 50 further out, so that it will be entirely outside the path of movement of the roller 51, so as not to be hit idly thereby. This action just described will set the parts at the pattern mechanism in normal position so that at the proper time the plunger carrier 45 will be moved towards the right, the plunger 14 will be lowered, together with the outer end of the lifting plate 16, so that its roller 18 will now be in the path of cam 19, and the return arm 50 will be set inward to be struck by the roller 51 when this comes around to restore the mechanism partway to normal position, this taking place after the lifting plate 16 has operated to raise the plunger 14 and change the yarn fingers.

50 55 The machine is provided with so-called

sinkers or web holders of substantially known form and operation.

In Fig. 5 only a few of the notches of the trick wheel are shown, this being for convenience of illustration.

70

I claim:

1. In combination in a knitting machine, a cam box, a needle advancing cam in said cam box, a post carrying the advancing cam, a shaft journalled in the cam box and extending horizontally, a cam member on the inner end of said shaft directly engaging the post for moving it vertically as the cam rotates, a ratchet on the outer end of the shaft for moving it step by step, a pawl for operating the ratchet and means for controlling the pawl to operate the ratchet at predetermined times.

75

2. In combination in a knitting machine, a cam box, a needle advancing cam in said cam box, a post carrying the advancing cam, a shaft journalled in the cam box and extending horizontally, a star-shaped cam member on the inner end of said shaft, directly engaging the post for moving it vertically as the cam rotates, a spring for pressing the post downwardly, a ratchet on the outer end of the shaft for moving it step by step, a pawl for operating the ratchet and means for controlling the pawl to operate 80 the ratchet at predetermined times.

90

3. In combination in a knitting machine, a needle operating cam, means for raising and lowering the same including a ratchet wheel and a star wheel connected to the ratchet wheel, a reciprocatory pawl for operating the ratchet wheel, a lever for operating the pawl to which it is pivoted and means for controlling the engagement between the pawl and the ratchet comprising a star wheel under the pawl upon which it rests, a second ratchet connected with the star wheel, and means for moving the said second ratchet step by step, substantially as described.

100

4. In combination in a knitting machine, a needle operating cam, means for raising and lowering the same including a ratchet wheel and a star wheel connected to the ratchet wheel, a reciprocatory pawl for operating the ratchet wheel, a lever for operating the pawl to which it is pivoted and means for controlling the engagement between the pawl and the ratchet comprising a star wheel under the pawl upon which it rests, a second ratchet connected with the star wheel and means for moving the said second ratchet step by step, said means comprising a slide arranged below the said second ratchet, a pawl carried thereby and engaging the ratchet and pattern mechanism 110 for operating the slide.

115

5. In combination in a knitting machine, a needle cam, means for raising and lowering it, a reciprocatory pawl for operating said means, a star wheel under the pawl upon 120

125

- which said pawl rests and which raises and lowers the pawl from and to the needle cam raising and lowering means, a ratchet connected with the star wheel for turning it, a horizontally movable slide, a pawl carried thereby to operate the ratchet, a bar pivotally connected with the slide, a reciprocating member for operating said bar when the latter is lowered into engagement therewith, and pattern mechanism for controlling the up and down positions of said bar, substantially as described. 65
- 5 10 15 20 25 30 35 40 45 50 55 60 65 70 75 80 85 90 95 100 105 110 115 120 125
6. In combination in a rotary knitting machine, a needle cam, means for raising and lowering the same, a reciprocatory pawl for operating said means, a rocking lever for operating the pawl, a horizontally disposed gear for rotating the knitting head, cam means thereon with connections therefrom to the rocking lever for operating the pawl, a cam on which the pawl rests to raise and lower it out of and into engagement with the needle cam raising and lowering means, and pattern controlled means for rotating said cam step by step, substantially as described. 80
7. In combination in a knitting machine, a rotary head, a needle operating cam, a post carrying the same, a crank member for raising and lowering the cam by engaging with its post, an arm on the shaft of the crank member, and a cam ring encircling the knitting head having high and low parts for operating said arm, and means for giving the ring a step by step movement. 90
8. In combination in a knitting machine, a rotary head, a needle operating cam, a post carrying the same, a crank member for raising and lowering the cam by engaging with its post, an arm on the shaft of the crank member, and a cam ring encircling the knitting head having high and low parts for operating said arm, and means for giving the ring a step by step movement, said means consisting of a pawl engaging teeth on the cam ring, and means for operating the pawl, substantially as described. 100
9. In combination, a rotary knitting head, a cam ring surrounding the same, a needle cam, means operated by the cam ring for raising or lowering the needle cam, a pawl for giving the cam ring a step by step movement, a pull bar, a slide connected to the pawl and operated by the pull bar, means for operating the pull bar, and pattern means for controlling the engagement of the pull bar with, and its disengagement from, its operating means, substantially as described. 110
10. In combination in a knitting machine, a rotary head, multiple feeds, a cam at each feed vertically adjustable, means at each cam for adjusting it, an operating member for each of said means, a slide and a pull bar pivotally connected thereto with means operated by the slide to make the operating member effective or ineffective, means for operating the pull bars, and pattern mechanism for controlling the engagement of the pull bars with their operating means, substantially as described. 115
11. In combination in a knitting machine, a rotary head, multiple feeds, a cam at each feed vertically adjustable, means at each cam for adjusting it, an operating member for each of said means, a slide and a pull bar pivotally connected thereto with means operated by the slide to make the operating member effective or ineffective, means for operating the pull bars, and pattern mechanism for controlling the engagement of the pull bars with their operating means, one of said operating members being a push pawl, and the other a pull pawl, substantially as described. 120
12. In combination in a knitting machine, multiple feeds including a stitch cam at each feed, means for raising and lowering said stitch cam, a ring encircling the knitting head and having high and low portions for operating both of the cam raising and lowering means, said ring being toothed, and means engaging the teeth for operating the ring step by step, substantially as described. 125
13. In combination in a knitting machine, a needle cam, means for raising and lowering the same, a cam ring encircling the knitting head, and means for operating the cam ring step by step to operate the cam raising and lowering means, substantially as described. 130
14. In combination in a multiple feed knitting machine, a needle raising cam at each feed, a trick wheel at each feed, a pull bar for each needle raising cam with means operated thereby for controlling the position of the cam, means for operating the pull bars, and pattern mechanism for controlling the times at which the pull bars individually will be operated by said means. 135
15. In combination in a knitting machine, a group of pull bars, connections from said pull bars to the knitting devices for varying the pattern, a counter, a pull bar with connections for operating the counter, means for operating the pull bars, means for raising and lowering the pull bars out of and into line with the operating means, and pattern means for controlling said raising and lowering movement, a part of the connections leading to the knitting devices being turnable about an axis and a part of the connections leading to the counter being turnable about the same axis, substantially as described. 140

In testimony whereof I affix my signature.

CHARLES C. KRIEBLE.
